United States Patent Office.

JOHN TAGGART, OF BOSTON, MASSACHUSETTS.

Letters Patent No. 83,888, dated November 10, 1868.

IMPROVED MACHINE FOR SPLITTING LEATHER.

The Schedule referred to in these Letters Patent and making part of the same.

To all persons to whom these presents may come:

Be it known that I, JOHN TAGGART, of Boston, in the county of Suffolk, and State of Massachusetts, have invented a new and useful Machine for Splitting Leather; and do hereby declare the same to be fully described in the following specification, and represented in the accompanying drawings, of which—

Figure 1 is a top view,

Figure 2, a front elevation, and

Figure 3, a transverse section of it.

Figure 4 is a horizontal section taken through its series of rotary cutters or knives.

Figure 5 is a horizontal section taken through the driving-belt of such knives or cutters.

Figure 6 is a vertical section taken through one of the end cutters and its supporting-frame, and one pair of the lateral adjusters of the said frame.

In such drawings, A denotes the frame of the machine. It has arranged within it, in manner as represented, a series of three feed-rollers, a b c, the upper and lower of which have pulleys, d e, fixed on their arbors. Around these pulleys a band, f, is extended, which may be either an elastic or an inelastic one. In case of it being an inelastic one, it should have means of taking it up or letting it out, so as to cause it to properly fit the pulleys.

The lower roller supports the middle roller, which should be made of an India-rubber sleeve, and a shaft or core to extend through it.

The journals of the upper and lowermost rollers of the series should be sustained in movable boxes, provided with adjusting-screws, h h h, by which the distance of one roller from the other, and their due positions relatively to the series of cutters, may be arranged or adjusted as circumstances may require.

In advance of the "bite" of the upper and middle feed-rollers, there is arranged a series of circular knives or rotary cutters, B B B, &c., each being fixed to the upper part of one of a series of vertical shafts, C C C, &c., which are arranged in a rectangular frame, D. This frame is grooved on its upper and lower edges to receive four tongues, f' f' f' f', which extend from four slides or adjusters, g g g g, which are so arranged and applied to the frame A as to be capable of being moved transversely thereof, in order to carry the series of knives or cutters, B B B, &c., either nearer to or further from the bite of the feed-rollers, as occasion may require, and particularly as the said knives or cutters may become reduced in diameter by being worn or sharpened. Each knife or cutter has directly underneath it and rests upon a tapering deflector, i, constituting the head of the shaft, to which the cutter is applied. This deflector is analogous to an inverted conic frustum, and is for two purposes, viz., that of supporting the circular knife, so as to prevent injurious vibrations of it, and also that of deflecting downward the lower portion or half of a sheet of leather while the said sheet may be in the act of being split by the knives or cutters.

Furthermore, the posts of each of the cutter-shafts should be adjustable vertically in the frame D, so as to enable all the cutters to be brought into one plane. Each cutter-shaft has a driving-pulley, k, fixed on it.

An endless band, l, proceeding from a driving-drum, m, is run along and against the fronts of the circumferences of half of the pulleys k, and against the rears of the remainder of the said pulleys, the same being as represented in the drawings, and so that when the said band is put in revolution it shall cause one-half of the shafts, on one side of the middle of the frame D, to revolve in a direction the reverse of that of the remainder of such shafts, the object being to cause half the number of cutters to revolve in one direction, and the other half of them to rotate in the other direction, so as, while all of them may be cutting the sheet, they shall operate also to stretch it in opposite directions from its middle, and thus prevent it from wrinkling. Suitable guide-rollers, o o o, are employed to keep the belt up to the pulleys of the shafts.

The frame D can slide longitudinally on the tongues f' f' f' f', and it has a mechanism applied to it to impart to it a reciprocating rectilinear motion, such mechanism being a lever, p, an eccentric, q, and a connector, q', of the eccentric and lever, the whole being as represented. The eccentric and the driving-drum m are placed on the same shaft, r.

In advance of the series of rotary cutters is a sharpener, E, composed of two grinders, s s, and a supporting-bar, t. While in movement, the knives or cutters extend and move between the grinders, and are kept sharp by them.

Furthermore, over the several rotary cutters, and extending down to them, or arranged with respect to them and the feed-rollers, is a curved guide-plate, F, the purpose of which is to guide from the cutters the upper portion split from the leather, and also to steady it close to the cutters, and, with the upper feed-roller, prevent it from coiling or wrinkling for some distance from them, while it may be passing from them.

There is also another guide-plate, G, attached to the frame A, and extended down and back from the middle feed-roller, in manner as represented, the purpose of the plate being merely to support the sheet of leather while being introduced to the feed-rollers, and while it may be in the act of being drawn forward by them.

One particular advantage of this machine, over the single-cutter or belt-cutter splitting-machines, is in its preventing the leather from wrinkling or cockling while being split. It has other advantages which leather-splitters can hardly fail to recognize.

In the said machine, I claim, as of my invention, the following:

The combination of a set of feeding-rollers, (provided with mechanism for operating them,) a series of rotary cutters, B, a carrying-frame, D, therefor, and mechanism for revolving such cutters, and imparting to the carrying-frame a reciprocating rectilinear move-

ment, in order to cause such cutters to cut a sheet of leather into separate pieces or sheets, when it is forced against them by the action of the feeding-rollers.

And in such a combination, I claim the employment or combination of a mechanism with the cutters, such as will cause those of them on one side of the medial vertical line of their sustaining-frame to revolve in directions opposite to those in which the remainder of such cutters are made to revolve, the same being for the purpose of stretching the leather in opposite ways while the cutters may be in action on it to cut it.

I also claim the combination and arrangement of sharpening-devices, *s s, t*, or mechanism, with the feed-rollers, and the series of rotary knives or cutters, their supporting-carriage or frame, and mechanism for operating it and them, so as to cause them to revolve, and at the same time to move together back and forth, in a manner to separate, when presented to them, a sheet of leather into two sheets, as described, the said sharpening-devices or mechanism being made to effect the

sharpening of the cutters while they may be in action, as stated.

I also claim, in combination with the feed-rollers, a series of rotary cutters, and their carrying-frame or carriage, as explained, devices for moving such frame toward the feed-rollers, from time to time, as the wear of the cutters may require.

I also claim, in combination with the feed-rollers, a series of rotary cutters and their carrying-frame or carriage, as explained, the series of tapering deflectors, *i*, arranged with the cutters and their shafts, as set forth.

I also claim the arrangement and combination of the steadyng and guide-plate *F*, with the feed-rollers, and series of rotary cutters, provided with mechanism for operating them, as described.

JOHN TAGGART.
